ELECTRIC FUSE

Edward Wilcox, Timperley, Altrincham, England,
assignor to Edward Wilcox & Co., Limited,
Wythenshawe, Manchester, England

Application July 29, 1947, Serial No. 764,453
In Great Britain February 2, 1944

Section 1, Public Law 690, August 8, 1946
Patent expires February 2, 1964

4 Claims. (Cl. 200—133)

1

This invention has reference to electric fuses of the kind comprising a fuse bridge or holder provided with contacts across which a cartridge fuse is connected, and a base provided with complementary contacts with which the contacts on the bridge or holder are adapted to be engaged when the latter is inserted into the base.

Hitherto in electric fuses of the kind referred to the contacts on the fuse bridge or holder have been bifurcated and the cartridge fuse has been mounted across the contacts by inserting the conducting caps on the ends of the cartridge fuse between the limbs of the contacts between which the cartridge fuse is tightly gripped when the contacts are inserted into complementary bifurcated or equivalent contacts on the base.

The object of the invention is to provide in an electric fuse of the kind referred to, improved means of securing the cartridge fuse between the contacts on the bridge or holder and also securing the contacts on the bridge or holder.

According to the invention, the contacts on the fuse bridge or holder of an electric fuse of the kind referred to, have associated with them screwed stems which screw through tapped holes in the contacts and are slidably mounted in abutments on the bridge or holder and the cartridge fuse is inserted between said stems, the screwing up of one or both of which clamps the fuse between the stems and also clamps the contacts against said abutments.

One embodiment of the invention is hereinafter further described with reference to the accompanying drawings whereof

Fig. 1 is a section of the base of the fuse,

Fig. 2 is a section of the fuse bridge or holder,

Fig. 3 is an elevation looking on the right hand side of Fig. 1,

Fig. 4 is an elevation looking on the left hand side of Fig. 2,

Fig. 5 is a section on the line V—V in Fig. 1,

Fig. 6 is a section on the line VI—VI in Fig. 2,

Fig. 7 is a perspective view of the two contacts mounted on the base,

Fig. 8 is a perspective view of one of the contacts mounted on the fuse bridge or holder,

Fig. 9 is a section showing the fuse bridge or holder fitted in the base and interlocked therein,

Fig. 10 is a section on the line X—X in Fig. 9, and

Fig. 11 is a fragmentary section of the fuse bridge or holder illustrating a modification of a detail hereinafter more particularly referred to.

Referring to the drawings, 12 is the base of the electric fuse and 13 is the fuse holder both made

2

of insulating material as is usual. The base 12 has mounted on it in recesses 14, 14a, tubular contacts 15, 15a formed with wide slots 16, 16a of width only slightly less than the full internal diameter of the contacts, and with narrow slots 17, 17a as described in British patent specification No. 544,122. The contacts 15, 15a are secured on the base by clamping screws 18, 18a and bushes 19, 19a of insulating material which are screwed into the ends of the base. The screws 18, 18a also serve to clamp the ends of the conductors which pass through the bushes 19, 19a into the bores 20, 20a of the contacts 15.

The fuse bridge or holder 13 is formed with sleeves 21, 21a in the opposing ends of which are seated the enlarged looped ends 22, 22a of resilient bifurcated contacts 23, 23a. The ends 22, 22a of the contacts 23, 23a are tapped to receive screw threaded tubular stems 24, 24a. The screwed stem 24 has fixed on it a sleeve 25 of insulating material which is freely rotatable and slideable in the sleeve 21 and is provided with an operating piece 26 by means of which it and the stem may be rotated. The screwed stem 24a has fixed on it a reel 33 of insulating material which is a free fit in the sleeve 21a. The ends 22, 22a of the contacts 23, 23a are formed with projections 27, 27a which take into recesses 28, 28a formed in the walls of the sleeves 21, 21a and the walls of the latter are formed with notches 29, 29a in which the limbs of the contacts are received, by which means the contacts 23, 23a are located in the ends of the sleeves and restrained against angular movement other than only sufficient to enable the contacts to align or adjust themselves to any slight inequalities in their setting or the setting of the contacts 15, 15a on the base 12.

The opposing ends of the screwed stems 24, 24a are concaved or internally coned to receive the correspondingly convexed, domed or coned conducting caps 30, 30a on the ends of a cartridge fuse 31 which is mounted between the stems.

To mount the cartridge fuse 31 between the stems 24, 24a the stem 24 is slackened back a little, the fuse is interposed between the stems and the stem 24 is screwed up, whereupon the fuse is centred and clamped between the stems in electrical connection with the contacts 23, 23a. Simultaneously, the contact 23a is pressed against its seat in the end of the sleeve 21a and the contact 23 is drawn against its seat in the end of the sleeve 21.

The notches 29, 29a in which the limbs of the contacts 23, 23a are received prevent undue spreading of the members of the limbs by the

screwing of the stems 24, 24a into the ends 22, 22a of the contacts.

The cartridge fuse 31 mounted across the contacts 23, 23a on the holder 13 is electrically connected across the contacts 15, 15a on the base 12, and the contacts on the holder and the base are interlocked, by first entering the forward or free ends 32, 32a of the contacts 23, 23a into the contacts 15, 15a through the wide slots 16, 16a and then moving the holder longitudinally relatively to the base to carry the limbs of the holder contacts 23, 23a into the narrow slots 17, 17a in the base contacts 15, 15a. Reverse movement of the holder breaks the interlock and allows of the holder being withdrawn from the base.

The ends 32, 32a of the holder contacts 23, 23a are normally of slightly greater width than the internal diameter of the base contacts 15, 15a so that when forced through the slots 16, 16a the ends 32, 32a enter the contacts 15, 15a with a snap action and the limbs of the contacts 23, 23a are also pressed together therein, thus ensuring good electrical contact between the two sets of contacts. The pressing together of the limbs of the holder contacts 23, 23a also has the effect of binding the enlarged rear ends 22, 22a of the contacts on the stems 24, 24a.

Where the cartridge fuse comprises one or more pieces of fuse wire contained in the fuse cartridge and clamped by the conducting caps 30, 30a a supply of spare fuse wire may be wound on the reel 33 for use as required. The reel 33 also serves as an operating piece for adjusting the stem 24a in the end 22a of the contact 23a. Alternatively, the stem 24a may have fixed on it an insulating sleeve 25a furnished with an operating piece 26a (as shown in Fig. 11) so that either stem may be adjusted to clamp and release the cartridge fuse 31.

The holder 13 may have in it a sight hole 34, Fig. 2, fitted with a pane of transparent material 35 through which can be seen whether or not a cartridge fuse is in position without removing the holder from the base.

In cases where the bridge or holder contacts are not bifurcated or the rear ends of the contacts are not looped, such ends of the contacts may be made with bosses for the formation of the tapped holes for the clamping stems 24, 24a.

In some cases springs or spring washers may be arranged on the stems 24, 24a between the contacts 23, 23a and the adjacent sleeves 21, 21a, which springs or spring washers tend to press the contacts towards each other and are compressed when the contacts are drawn towards the sleeves by the screwing up of the stems. Alternatively,

springs may be arranged in the bores of the sleeves between the outer ends of or collars on the stems and plugs screwed into the sleeves, the screwing up of the plugs causing the springs to force the front ends of the stems into yielding engagement with the conducting caps 30, 30a on the ends of the cartridge fuse 31. These arrangements provide that after the stems 24, 24a have been adjusted a blown cartridge fuse can be removed and replaced by a fresh one with a snap-action without interfering with the stems.

I claim:

1. A contact bridge member for electric fuses comprising an insulating holder having axially aligned tubular ends and an intermediate connecting portion, two contact members each of approximately U-shape and having their closed ends in the form of an internally screw threaded circular loop, one contact member being disposed against the inner face of each tubular end of the holder and free for axial movement, and two screw stems, one screw stem being entered into each tubular end of the holder and screwing into the loop of the adjacent contact member and the two stems being adapted to engage the opposing ends of a fuse inserted between them alongside the said intermediate connecting portion.

2. A contact bridge member as claimed in claim 1 in which key means are provided to restrain the contact members angularly.

3. A contact bridge member as claimed in claim 1 in which the free ends of the contact members are received and spaced in axial slots in the respective tubular ends of the holder.

4. A contact bridge member as claimed in claim 1 in which key means are provided to restrain the contact members angularly and in which the free ends of the contact members are received in axial slots in the respective tubular ends of the holder.

EDWARD WILCOX.
